George W. Cook

UNITED STATES PATENT OFFICE.

GEORGE W. COOK, OF CHICAGO, ILLINOIS.

PIPE-WRENCH.

SPECIFICATION forming part of Letters Patent No. 283,378, dated August 21, 1883.

Application filed March 24, 1883. (No model.)

To all whom it may concern:

Be it known that I, GEORGE W. COOK, a citizen of the United States, residing at Chicago, in the county of Cook and State of Illinois, have 5 invented a new and useful Improvement in Pipe-Wrenches, of which the following is a specification.

The nature of the invention consists in a device which, when attached to the common 10 wrench, known as a "monkey-wrench," forms a rod or pipe wrench; and the objects of the invention are, first, to furnish a device which is readily attached to and detached from the monkey-wrench, thereby utilizing the monkey- 15 wrench as a combined tool; second, to furnish a device which can be attached to wrenches already constructed by a slight alteration of the wrench, which can be made by any ordinary mechanic, therefore the device can be manufactured and sold separate from the wrench; 20 third, to produce a combined wrench having other adjustments than that had by means of the thumb-screw of the monkey-wrench, and thereby have a more convenient and reliable 25 tool. I accomplish these objects by the mechanism illustrated in the accompanying drawings, in which—

Figure 1 is a plan view of the wrench with my improvement attached; Fig. 2, a plan view 30 of the upper jaw of the wrench as prepared to receive my attachment; Fig. 3, a perspective view of the invention when detached from the wrench; Fig. 4, a section through Fig. 1 and the pipe *g*, showing the adjustment when in 35 operation; Fig. 5, a perspective view of the dog *f*.

Similar letters refer to similar parts throughout the several views.

The entire attachment, as shown at Fig. 3, 40 is made out of steel, or any suitable metallic substance.

The elongated part *B* constitutes the frame of the device. In one end of this frame I fasten, by means of rivets or otherwise, the block 45 *B'*; at the other end the block *B''*. These two blocks form the bearings upon the jaw of the wrench *A*, when the device is attached to the wrench and ready for operation. The block *B'* is constructed with one or more projections, 50 as shown at *C'*. These projections correspond with and fit into the notches *C* upon the head

of the wrench, and form the points of adjustment and lock of the attachment to the head of the wrench. The block *B''*, which has its bearings underneath the jaw of the wrench, is 55 constructed with a groove corresponding with the rounded back of the dog *f*, at which point the dog is hinged by means of the pin *e*. This pin projects from both ends of the dog into the sides of the frame *B*. The holes *d* in the frame 60 are somewhat larger than the diameter of the pin, in order that the entire bearing shall come upon the rounded part of the dog, instead of the pin, while the tool is being operated.

Upon the top of the block *B''*, I place the 65 spring *j*, one end of which has a bearing upon the back of the dog *f*. By means of this spring the dog is pressed forward and brought in close contact with the pipe *g*, while making the proper adjustment, to prevent the dog from slipping 70 when the wrench is being turned in the direction indicated by the arrow shown at Fig. 4.

The countersunk points *D* are the receptacles for the end of the thumb-screw *E*, by which means the attachment is held to its place while 75 handling the wrench.

In operating the combined tool the device is placed upon the head of the wrench, as shown at Fig. 1, the projecting tooth *C'* being placed in one of the notches of *C*, which will bring the 80 dog *f* in a position corresponding with the size of the pipe to be held or turned. The pipe is then brought in contact with the dog by means of the movable jaw of the wrench, after which, by a slight manipulation of the thumb-screw 85 of the monkey-wrench, and with the pressure of the spring *j*, some one of the teeth of the dog is readily placed at a proper angle to take a firm and reliable hold on the pipe. By turning the wrench in the direction indicated by the 90 arrow, as shown at Fig. 4, and by a reverse motion of the wrench, the spring behind the dog will give sufficiently to let the wrench turn in that direction with perfect ease.

I do not confine myself to the one projection, 95 *C'*, as shown, on the block *B'*; nor to any particular number of the notches *C*, as in the larger size tools, where more strength and greater scope of adjustment are required, two or more of these projections and an additional number 100 of the notches would be preferable. Neither do I confine myself to the thumb-screw *E* or the

countersunk points D, as a spring or other simple devices may be used instead.

What I do claim, and desire to secure by Letters Patent, is—

- 5 1. In combination with a monkey-wrench, the device herein described, consisting of the frame B, the block B², the block B', the dog f, and the spring j, all substantially as set forth.
2. In combination with the frame B, block

B², block B', dog f, and spring j, the jaw A, so provided with the ratchet-notches C, operative with the projecting tooth C', substantially as and for the purposes set forth.

GEORGE W. COOK.
